VOLTAGE REGULATOR

Application filed March 15, 1928. Serial No. 281,976.

The present invention relates in general to gaseous conduction apparatus and in particular to a device for regulating the line voltage in a system subject to voltage or current changes or both.

For voltage regulation purposes in radio supply circuits and elsewhere, it has been proposed heretofore to connect across the line a gaseous discharge device in which the anode 10 consists of a solid cross-sectioned body positioned within a hollow cathode. The gas employed is of the monatomic group, ordinarily helium, which commends itself chiefly by way of minimizing cathode disintegration 15 under conditions of fairly high current and also in requiring a purification process simpler than in the case of neon or argon.

Tests conducted by me have demonstrated the fact that in prior art tubes including 20 those filled with helium, there is considerable instability of operation manifested by way of irregular output and other disorders. The origin of the disturbances is hard to ascertain but I believe it to reside in the region of 25 the positive electrode and to be a function of voltage drop at this point, which discovery is based upon the fact that when the voltage loss at that surface is reduced, the tendency of the regulator to produce uniform terminal 30 voltage becomes pronounced even under conditions of variable input.

While there are many factors which contribute to potential loss at the electrode, the decrease in each serving to produce greater 35 stability, the condition of instability is particularly emphasized in the case of prior art anodes of solid construction and in the event, the helium or other gas contains an electro-negative impurity e. g. nitrogen or 40 oxygen. Furthermore, the discharge in the neighborhood of a positive member having small area is likely to show unstable characteristics under conditions of appreciable load, producing unsatisfactory performance 45 as a current by-pass.

I have also found by experience that instability in regulator tube is much more likely at relatively high than at low gas pressure; there appears to be a definite pressure 50 applicable to each of the rare gases below

which a tube of given size and design remains stable even under the most unfavorable circumstances. The transition from the unstable to stable conditions at the gas pressure referred to is to be sharply distinguished 55 from the case where gas is entirely removed from the envelope, to produce a hard vacuum, by which uniformity of operation and lack of sensitiveness may be secured. In the present invention, the presence of gas is not only desirable but essential and it is apparent that a gaseous conduction device operating under stable conditions is fundamentally different from a strictly electron 60 discharge apparatus.

I propose to modify the construction of prior regulators in order to reduce to a stable factor the anode losses, at the same time securing all the advantages obtainable from the use of helium. The modification is centered about a novel form of anode which has been found to operate well in conjunction with a hollow cathode. The modification takes on simple construction and design without the necessity of critical dimension, thus 70 lending itself readily to ease of manufacture and mass production. It also has a high degree of reproducibility, i. e. all tubes made in accordance with the design have substantially the same internal characteristics. 75

For the purpose of illustrating the genus of the invention, a typical embodiment is shown in the accompanying drawing.

The figure shows an envelope 1 formed of glass and terminating in a press 2. Within 85 the envelope and supported from the press in suitable manner e. g. by fusing the lead-in wires in the glass, there is a hollow cathode 3 of closed perimeter preferably shaped as an open-ended cylinder and made of refractory material. The anode 4, also refractory, is smaller in dimension than the cathode, a condition which is decidedly beneficial in operation. The anode has a shape conforming to that of the cathode, and is positioned 90 within the latter preferably in coaxial relation therewith, i. e. concentrically in the lateral direction, and mid-way between the cathode edges in the direction of the principal axis. Numeral 5 designates a wire or 95 100

additional electrode employed for starting purposes; this electrode is located relatively close to the inner surface of the cathode as shown.

5 Attached to the cathode, there is a metallic capsule 6 containing substance for liberating by heat treatment, active electro-positive material; this substance is preferably a mixture of two or more alkali metals, 10 e. g. caesium and potassium, as claimed in my application Serial No. 204,320 entitled "Rectifier tubes" with a preferred proportion of five parts potassium to one part caesium. As pointed out in the application 15 supra, the potassium takes on the rôle of getter leaving to the caesium, the function of minimizing potential drop. The capsule preferably should be insulated from the cathode and for this purpose, I provide a metallic wire in two sections insulatingly separated by a glass bead 7. The receptacle or container 1 is filled with a gas of the monoatomic group, preferably helium at a pressure ranging from 15 to 25 millimeters of Hg. The 20 manufacturing process may be completed by furnishing a base for the envelope carrying contact plugs.

In operation, the regulator is connected across the line, in case of a "B" eliminator 25 ordinarily of 90 volts, cathode 3 to the negative side, anode 4 to the positive side and a tap taken from a point in the circuit where the voltage is sufficiently high to provide the necessary starting potential for auxiliary 30 anode 5. Upon initiation of a discharge between the cathode and operating anode, a current path is established in shunt to the load which acts as a by-pass for excess current caused by potential variations.

35 While anode 5 may be used solely as a starting expedient, e. g. by providing a suitable method of rendering it inoperative upon completion of the starting function, it has been found advantageous to continue the discharge throughout the entire operating period of the regulator; the auxiliary flow of current appears to raise the intensity of ionization within the hollow cathode to a uniform level, making for improved operation.

40 A tube as described, has the desirable property of producing a substantially constant voltage drop across its terminals regardless of the magnitude of current passing, and has a great degree of stability. The current-voltage characteristic shows a substantial portion in parallel to the current axis which portion is selected for operation, so that notwithstanding substantial changes in current 45 through the tube, no substantial voltage variations take place across the terminals.

Experience has shown that inside my novel hollow-anode device, the potential drop in the vicinity of the positive electrode, i. e. 50 the voltage necessary to draw electrons to

the anode surface, is materially less than in the case of a member having solid cross-section. While the reason for the voltage difference is difficult to ascertain correctly, and accordingly I do not wish to be limited to my explanation, I believe it to reside in the fact that within the hollow electrode, there is a region of intense ionization giving rise to electro-positive ions of large mass and small mobility which reduce the negative space charge of the electrons moving to the anode. The glow represents a congregation of positive ions which act to draw other electrons through the open ends of the cylinder with the result that the edges or rims over which the stream pours, offers a very low potential loss to the passing current. Inasmuch as the voltage drop is determined, not directly from the electron stream, but rather from the ionization caused by the same, a secondary function, the discharge remains stable even under conditions of high current and when employing an anode of relatively small dimension. The intense ionization referred to, also counteracts the tendency of the electro-negative impurities, drawn to the region by the action of the electric field, from raising the anode loss.

This phenomenon may be considered from another point of view. As is well known, in devices of this kind having solid anodes or anodes whose active surfaces face the active surfaces of the cathode, the bombardment of the anode by the gas particles produces a dull velvety surface on the anode which results in a greater anode drop of potential. Such surface is less conducting and causes a greater loss during discharge. In devices of the prior art, the anodes were such that the total active surface thereof became velvety. In my device, the surface of the anode which is bombarded and the active surface of the anode are different. Those electrons which go very fast, hit the outer anode surface, causing the velvety appearance. But most of the current carrying particles take a curved path to the inner surface of the anode, which is probably the surface having the lowest drop or anode loss, and in doing so are slowed down considerably. Hence there is no or little anode bombardment and no velvety surface is formed on the inner surfaces of the anode. In a broader sense, any anode having reentrant or concave surfaces would function in substantially the same manner.

115 It is obvious that the velvety outer surface of the anode may be obtained by bombardment either before or after the final manufacture of the tube. Ordinarily it is developed in use of the tube.

120 While I have shown a cathode approximately three times as long as the anode which has given satisfactory results at test, it is to be understood that these relative dimensions are not important but may be varied within 130

wide limits; in the same manner, the relative diameters may be changed. Due to the arrangement and design of electrodes, and the pressure of the gas, the degree of stability 5 is exceedingly marked, giving the tube a non-critical characteristic under all conditions of operation and furnishing a safe margin of stability to enhance reproducibility and mass production. The cylindrical form 10 of anode offers an advantage during manufacture in that it may be heated by a high frequency discharge during the pumping process, thus effectively removing the gas held by occlusion.

15 In reducing the loss in potential at the positive electrode when stabilizing the discharge, the hollow-anode type of space current device offers a greatly improved voltage regulating property. Since the anode drop 20 is low, it is not so dependent upon the negative space charge in its vicinity and is, therefore, a small factor in the voltage drop of the tube. The tube exhibits only small variation 25 with changing current, the total potential drop remaining practically constant, even under conditions of varying load.

I claim:

1. A gas discharge device comprising the combination with an envelope containing a 20 gas at a reduced pressure, of a cathode, an anode within the cathode, and a source of alkali metal vapors supported by but insulated from one of said electrodes.

2. A gaseous regulator tube for regulating 25 the voltage across a direct current source comprising, a gas tight vessel containing ionizable gas at a pressure sufficient to maintain a glow discharge between two spaced electrodes therein, a hollow relatively large 40 area cathode in said vessel adapted to be connected to the negative terminal of said source, and a hollow anode of smaller area than said cathode disposed inside said cathode and adapted to be connected to the positive terminal 45 of said source so as to maintain through said gas a regulating glow discharge with said cathode at which a substantially constant voltage is secured across said source.

3. A gaseous regulator tube for regulating 50 the voltage across a direct current source comprising, a gas tight vessel containing ionizable gas at a pressure sufficient to maintain a glow discharge between two spaced electrodes therein, a hollow cylindrical relatively 55 large area cathode in said vessel adapted to be connected to the negative terminal of said source, and a hollow cylindrical anode of smaller area than said cathode disposed inside said cathode and adapted to be connected to the positive terminal 60 of said source so as to maintain through said gas a regulating glow discharge with said cathode at which a substantially constant voltage is secured across said source.

65 4. A gaseous regulator tube for regulating

the voltage across a direct current source comprising, a gas tight vessel containing ionizable gas at a pressure sufficient to maintain a glow discharge between two spaced electrodes therein, a hollow relatively large 70 area cathode in said vessel adapted to be connected to the negative terminal of said source, a hollow anode of smaller area than said cathode disposed inside said cathode and adapted to be connected to the positive terminal 75 of said source so as to maintain through said gas a regulating glow discharge with said cathode at which a substantially constant voltage is secured across said source, and an additional electrode for maintaining 80 throughout said regulating discharge an independent discharge inside said vessel ionizing the gas therein.

5. A gaseous regulator tube for regulating 85 the voltage across a direct current source comprising, a gas tight vessel containing ionizable gas at a pressure sufficient to maintain a glow discharge between two spaced electrodes therein, a hollow relatively large area 90 cathode in said vessel adapted to be connected to the negative terminal of said source, a hollow anode of smaller area than said cathode disposed inside said cathode and adapted to be connected to the positive terminal of 95 said source so as to maintain through said gas a regulating glow discharge with said cathode at which a substantially constant voltage is secured across said source, and an additional electrode disposed inside said cathode for maintaining therewith throughout 100 said regulating discharge an independent discharge ionizing the gas in the vessel.

6. A gaseous regulator tube for regulating 105 the voltage across a direct current source comprising, a gas tight vessel containing ionizable gas at a pressure sufficient to maintain a glow discharge between two spaced electrodes therein, a hollow relatively large area cathode in said vessel adapted to be connected to the negative terminal of said source, and a hollow anode of smaller area than said cathode disposed inside said cathode and adapted to be connected to the positive terminal 110 of said source so as to maintain through said gas a regulating glow discharge with said cathode at which a substantially constant voltage is secured across said source, the gas in said vessel including a monatomic inert gas and alkali metal vapor.

In testimony whereof, I have signed my 115 name to this specification this 13th day of March, 1928.

PERCY L. SPENCER.
